SKI BINDING

Miles Pennybacker, Redding, Conn.

Application August 25, 1948, Serial No. 46,018

10 Claims. (Cl. 280—11.35)

2

This invention relates to a ski-binding adapted to connect a ski boot to a ski.

Conventional ski-bindings generally include means to rigidly hold the toe or forward portion of the ski boot sole fixed with respect to the ski and to permit the boot heel to move up and down with respect to the ski to compensate for heel motion during walking and climbing. This type of ski-binding has been widely used and accepted for many years even though it has disadvantages from a safety viewpoint and does not provide as good control as when the heel is held firmly to the ski. For example, no provision is made in this type binding to instantly liberate the skier when abnormal shock or strain is encountered, as in a bad spill or twist, which in many instances results in broken bones or bad sprains for the skier.

It is an object of the present invention to provide a novel ski-binding in which both the toe and heel of the ski boot are securely and rigidly held against the ski during all normal conditions but instantly and automatically released when the heel is subjected to abnormal forces, thus providing for automatic release of the skier in the event of a bad fall or twist.

Another object of this invention is to provide a ski-binding in which the heel of the ski boot is permitted sidewise movement during a twist of dangerous magnitude only, thereby releasing the skier and minimizing the hazard of broken bones.

Another object of the present invention is to provide a novel ski-binding in which controlled spring tensioned means is arranged to normally exert rearward thrust upon the toe of the ski boot which in turn holds the boot heel flat against the ski during all normal skiing conditions, but permitting the heel to raise only when a predetermined forward force on the boot is reached. This permits the spring tensioned means to yield sufficiently to allow instant separation of the boot from the ski to thereby liberate the skier.

Still further, and more limitedly, the present invention contemplates the provision of a ski-binding in which a predetermined pressure is exerted against the toe of the ski boot which in turn holds the heel of the boot against a heel member; in which said heel is movable with respect to the ski only when a predetermined forward or sidewise thrust imparted to the ski boot takes place; and in which an adjustable clamp is employed to vary the force required to release the boot from the ski.

Various other objects and advantages of the invention will be pointed out in the following description and claims and illustrated in the ac-

companying drawings, which disclose, by way of example only, the principle of the invention and one mode, which has been employed, of applying that principle.

5 Fig. 1 is a side elevational view of a ski boot and a portion of a ski illustrating one embodiment of the novel ski binding which is shown in clamping condition.

Fig. 2 is a plan view of Fig. 1.

10 Fig. 3 is a side elevation similar to Fig. 1 but showing the boot in dotted lines and the ski-binding in its emergency-release position.

Fig. 4 is a perspective detail of one form of the movable heel member.

15 Fig. 5 is an enlarged side elevational view of the adjustable clamp shown in Fig. 1 and that portion of the ski to which it is attached.

Fig. 6 is a top view of Fig. 5 with the clamp shown partly in section.

20 Figs. 7 and 8 are fragmentary detail views of the clamp in open position.

Fig. 9 shows a modified construction of the movable heel member, and

Fig. 10 is a top view of Fig. 9.

25 Referring now to the accompanying drawings, reference character S generally indicates the central portion of a conventional ski, or that portion of the ski which supports the ski boot B. The novel ski-binding, in general, comprises a toe retaining means T and a heel retaining means H which will be separately described.

30 In conventional ski-bindings, the toe of the ski boot is usually rigidly held to the ski by toe irons fastened to the ski, and the toe of the ski boot is pushed forwardly into the toe irons by a spring pressed cable which is laid around the heel of the boot and drawn forwardly by a toggle clamping member mounted upon the ski forwardly of the boot. In the present ski-binding, the procedure is somewhat reversed as the toe of the ski boot B is forced rearwardly against the movable heel retaining member H by a spring tensioned cable 12, which is drawn rearwardly by a toggle clamping member C mounted on the ski S rearwardly of boot B.

35 The toe retaining means T will be described first, and by reference to Figs. 1 and 2 it will be observed that the ends of cable 12 are secured to a fastening element 13, and that cable 12 is guided in its movement longitudinally of the ski S by a pair of conventional plates 14 screwed to the sides of the ski and each provided with a pair of ears 15 and a pin 16.

clamping member C by a strong spring 17. The forward end of this spring is securely fastened to said element 13 and the rearward end is adjustably secured to a bail 18 through rod 23 and nut 24 as best shown in Figs. 5 and 6. The ends of bail 18 are pivotally connected by a pin 19 to clamping lever 20, and the lever in turn is pivotally connected by a pin 21 to a U-shaped connector 22 as best shown in Figs. 7 and 8. Any suitable and convenient means may be employed to hold connector 22 in various positions of adjustment upon ski S for the purpose of varying the tension of spring 17. One means is shown in Figs. 5 to 8 as comprising a rectangular stud 25 having a groove 26 near its free end. This stud is secured to and projects downwardly from connector 22 and its groove 26 cooperates with any selected T-shaped opening 27 in the top portion of channeled bracket 28 which is rigidly attached to the ski by screws 29.

Referring now to heel retaining means H, and for the present to the form shown in perspective in Fig. 4, numeral 30 indicates a bracket the base 31 of which is securely fastened to ski S just rearwardly of the boot heel 32 as clearly shown in Figs. 1 and 2. Pivoted for swinging movement upon a pin 33, carried by the upper end of bracket 30, is a T-shaped member 34 having a curved heel engaging bar 38. If desired, this bar may be covered with a resilient material, such as rubber, to insure a firm grip between it and the conventional heel groove 35 of boot B when the latter is held in clamped position upon ski S.

Operation

Operation of the ski-binding above described is extremely simple. To attach boot B to ski S, the first step is to shift clamping member C to its open position so that cable 12 may be drawn forwardly without any tension upon spring 17. Curved bar 38 is then placed in groove 35 of heel 32 as clearly shown in Fig. 1, and the looped end of cable 12 is then laid around the boot toe 36 in engagement with the upper surface of the sole of the boot. Clamping lever 20 is then rocked to its closed position and in so moving draws cable 12 rearwardly and exerts an initial tension upon spring 17 to firmly lock boot B between said cable and heel bar 38. Boot B is now rigidly attached to ski S and so held during all normal skiing conditions, but is instantly and automatically released to liberate the skier should abnormal shock or strain be encountered, as in a bad spill.

To explain how the boot is automatically released during abnormal skiing conditions, attention is directed to Figs. 1 and 3. In Fig. 1 the ski boot B is shown clamped to ski S through rearward pressure of cable 12 holding heel 32 in engagement with heel retaining means H. It will now be obvious that upward movement of the boot heel 32 is controlled by the tension placed upon spring 17, and that before the heel can rise from the ski, it is necessary for the boot to slightly shift forward or longitudinally with respect to the ski, thus increasing the tension placed on the spring 17. Heel engaging bar 38 swings on a radius about its pivot 33, as indicated by dotted line A in Fig. 1, and consequently no upward movement of heel 32 can take place until spring 17 is stretched beyond its initial tension to permit forward movement of cable 12. The construction is such that automatic release of boot B from ski S can be predetermined through the tension placed upon spring 17, and this ten-

sion can be varied depending upon which T-shaped opening 27 stud 25 is engaged with.

There are times when it is highly desirable to instantly release the ski boot from the ski during a bad twist to prevent injury to the skier. The modified heel retaining means R, shown in Figs. 9 and 10, is designed to operate in exactly the same manner as the heel retaining means H shown in Fig. 4, but in addition permits release of the boot when sidewise movement during a twist of dangerous magnitude is encountered. In this form, the heel retaining means R comprises a post 37 having its lower end rotatably mounted in a cup-shaped plate 39 and its upper end formed into an eye 40. Plate 39 is attached to ski S rearwardly of boot heel 32 by screws 41 as clearly shown in Fig. 9. A T-shaped member 42, somewhat similar to member 34, is provided with a curved heel engaging bar 43. The member 42 is pivotally connected with the eye 40 of post 37 by an eye 44 formed upon the member in the manner illustrated. By a study of Figs. 9 and 10, it will be apparent that bar 43 not only swings through a vertical arc relative to its pivot 40—44 but is also capable of swinging in a horizontal arc about the post 37 to permit sidewise movement of heel 32 with respect to ski S to liberate the skier during twists of dangerous magnitude but firmly holding the heel against the ski during all normal skiing conditions.

Although a preferred embodiment of the invention has been illustrated and described, it will be obvious to those skilled in the art that various modifications may be made without departing from the spirit thereof, and it is the intention therefore to be limited only as indicated by the scope of the following claims.

The invention claimed is:

1. In a ski-binding adapted to rigidly connect a ski boot to a ski during all normal skiing conditions but capable of automatically releasing said boot to liberate the skier when abnormal shock or strain is encountered, comprising, a heel member pivoted for releasable connection with the heel of said boot; means engageable with the toe of said boot to normally thrust the heel of the boot against said pivoted heel member; and means to vary the thrust of said toe engaging means to permit swinging movement of said heel member out of engagement with said boot heel when a predetermined forward thrust on the boot relative to the ski is reached.
2. In a ski-binding of the class described, the combination comprising a bracket secured to a ski rearward of the position occupied by a ski boot; a heel-engaging member pivotally attached to said bracket and adapted to engage within a groove in the heel of a ski boot; a toe-cable engageable with the toe of said boot; means to draw said cable rearwardly to lock said boot upon the ski between said cable and heel-engaging member during all normal skiing conditions; and means including a spring and toggle clamp to so tension the cable that a predetermined forward movement of the boot relative to the ski is necessary before the boot is automatically released from the ski.
3. In a ski-binding wherein both the sole and heel of a ski boot are rigidly secured to a ski during all normal skiing conditions but automatically released to liberate the skier when abnormal shock or strain is encountered comprising, in combination, a pivoted heel-engaging member arranged for swinging movement in vertical and horizontal arcs relative to the ski;

means to normally exert a rearward thrust on the boot to hold the heel thereof in engagement with said heel member including a toe cable; and means to vary the tension of said cable in accordance with the size of ski boot and weight of the skier substantially as set forth and for the reasons specified.

4. In a ski-binding adapted to releasably connect a ski boot to a ski comprising the combination of a pivoted heel-engaging member arranged to swing in vertical and horizontal arcs relative to the ski; and means including a toe cable and spring to impart rearward thrust to the ski boot to hold the heel thereof in engagement with said swingable heel-engaging member during all normal skiing conditions but capable of yielding to automatically release said boot through swinging movement of said heel-engaging member to liberate the skier when abnormal shock or twist is encountered.

5. In a ski-binding adapted to releasably connect a ski boot to a ski comprising the combination of a heel-engaging member arranged for pivotal movement in horizontal and vertical arcs relative to the ski; means to impart rearward thrust to said boot to hold the heel of the boot against said heel-engaging member during all normal skiing conditions; and means to predetermine the thrust of said last named means including a spring and toggle clamping element.

6. In a ski-binding adapted to rigidly connect a ski boot to a ski during all normal skiing conditions but capable of automatically releasing said boot to liberate the skier when abnormal shock or strain is encountered, comprising, a heel member pivoted for releasable connection with the heel of said boot; means engageable with the toe of said boot to normally thrust the heel of the boot against said pivoted heel member; and means to vary the thrust of said toe engaging means to permit swinging movement of said heel member out of engagement with said boot heel when a predetermined forward and upward thrust on the boot relative to the ski is reached.

7. In a ski-binding adapted to rigidly connect a ski boot to a ski during all normal skiing conditions but capable of automatically releasing said boot to liberate the skier when abnormal shock or strain is encountered, comprising the combination of, a heel member pivoted for releasable connection with the heel of said boot; a toe cable engageable with the toe of said boot to normally thrust the heel of the boot against said pivoted heel member; a toggle clamping member; a spring connecting said cable with said clamping member; and adjustable means to vary

the tension of said spring to determine the force with which said toe cable holds the boot heel against said heel engaging member.

8. In a ski-binding adapted to rigidly connect a ski boot to a ski during all normal skiing conditions but capable of automatically releasing said boot to liberate the skier when abnormal shock or strain is encountered, comprising, a heel engaging member pivoted for swinging movement in vertical and horizontal arcs relative to the ski for releasable connection with the heel of said boot; a cable engageable with the toe of said boot to normally thrust the heel of the boot against said pivoted heel member; a fastening element for securing the ends of the cable together above the top surface of the ski; a toggle clamping member; and a spring connecting said fastening element with said clamping member substantially as described and for the purposes set forth.

9. In a ski-binding as specified in claim 8 wherein the toggle clamping member includes a lever adjustably mounted upon the ski to vary the tension of the cable spring.

10. In a ski-binding adapted to releasably connect a ski boot to a ski, the combination of a pivoted heel-engaging member mounted upon the ski for swinging movement in vertical and horizontal arcs relative to the ski for releasable engagement by the heel of said boot; a cable engageable with the toe of said boot and guided for movement longitudinally of the ski; means to pull said cable against the toe of said boot to normally hold the heel engaged with said heel-engaging member; and means to vary the thrust of said cable against said boot toe to permit swinging movement of said heel-engaging member out of holding engagement with said boot heel when a predetermined forward thrust on the boot relative to the ski is reached.
